UNITED STATES PATENT OFFICE

2,604,344

DOOR LATCH

Bert A. Quinn, St. Paul, Minn.

Application May 16, 1946, Serial No. 670,094

8 Claims. (Cl. 292—226)

1

My invention relates to an improvement in door latch wherein it is desired to provide a simple and effective construction.

It is an object of the present invention to provide a door latch which may be constructed of an extremely small number of parts and which will be effective to serve its intended purpose.

It is a further object of the present invention to provide a door latch construction which may be constructed of a small number of parts which may for the most part be stamped out on a punch press or the like. As a result the parts employed may be manufactured at extremely low cost and in considerable volume in a short period of time.

A feature of the present invention lies in the provision of a door latch which may be easily secured in place upon a door. In attaching the latch to the door, it is only necessary to cut a notch in one edge of the door, secure a base plate in the notch, and to attach the latch handle portion to overlie the base plate. Thus the latch may be secured in place in an extremely short period of time.

It is a feature of the present invention to provide a door latch construction which requires no circular pivot connecting the handle elements to the door. The handle element is mounted upon the base bracket for swinging movement relative thereto in such a manner that the base plate and handle require no circular pivot connecting the same. As a result my door latch requires no assembly and may be furnished in unassembled form for assembly upon attachment.

A further feature of the present invention resides in the provision of a handle element which is modernistic in appearance and attractive in design. When in place upon a door my latch adds to, rather than detracts from the appearance of the door.

These and other objects and novel features of my invention will be more clearly and fully set forth in the following specification and claims.

In the drawings forming a part of my specification:

Figure 1 is a perspective view of my latch in position upon a door.

Figure 2 is a sectional view through the door, the latch, and the keeper showing the relative positions thereof when the latch is in locked position.

Figure 3 is a view similar to Figure 2 showing a latch in open or unlocked position.

Figure 4 is a perspective view of the base plate.

Figure 5 is a perspective view of the locking plate underlying the handle element.

2

The door latch A is formed of a single strip of flat sheet metal or the like, preferably bent into substantially U-shape. The free ends of the body form handle elements, one end 10 lying on one side of the door B and the other handle end 11 lying on the opposite side of the door B. The handle element illustrated in general by the numeral 12 is provided with an elongated slot 13 formed in the bend between the handle end 10 and the substantially flat intermediate portion 14 of the handle element. A slight off-set 15 is preferably formed in the handle element 12 substantially centrally between the handle ends 10 and 11 for a purpose which will be later described in detail. A central aperture 18 extends through the intermediate portion 14 and a pair of opposed notches 16 and 17 are formed in the intermediate portion 14 on the side of the intermediate portion 14 most closely adjacent the handle end 11.

20 As best illustrated in Figure 4 of the drawings the base plate or bracket 19 of my latch comprises a flat panel 20 having end flanges 21 and 22 thereupon. The end flanges are of greater width at one end than at the other as the panel 19 is usually inclined relative to the edge of the door. The end 23 of the flange 21 is longer than the edge 24 thereof and the free edge 25 of the flange 21 is designed to lie substantially flush with the edge of the door B.

25 The edge 26 of the flange 22 is longer than the opposite edge 27 thereof and the free edge 29 of the flange 22 is designed to lie flush with the edge of the door. As a result the panel 20 of the base bracket is supported on an angle relative to the edge of the door.

30 The panel 20 is provided with spaced apertures 30 through which attaching means may extend to attach the base plate to the door. In Figures 2 and 3 of the drawings I disclose wood screws 31 35 extending through the apertures 30 and into the door to hold the base plate in proper position thereupon.

35 A pair of spaced apertures 32 are provided in the base plate 20. Conical springs 33 extend through these apertures 32, the base of these springs being of sufficiently large diameter to be engaged beneath the base plate panel 20. Thus when the base plate 19 is attached to the door the springs 33 are anchored between the base plate panel 20 and the door and extend outwardly toward the edge of the door from the panel 20.

40 A pair of hook shaped flanges 34 and 35 extend outwardly from an edge of the panel 20 near the top and bottom flanges 21 and 22. The

flanges 34 and 35 are provided with hook ends 36 and 37 respectively, which extend substantially parallel to the panel 20. These hook flanges 34 and 35 are for the purpose of hingedly connecting the base plate and the handle element 12.

A latch plate 39, preferably of relatively resilient material includes a flat panel 40 approximately equal in width with the intermediate portion 14 of the handle element 12 having a pair of opposed notches 41 and 42 therein substantially identical with the notches 16 and 17 of the handle element 12. An aperture 43 extends through the plate 40, the position of the aperture 43 substantially corresponding with the position of the aperture 18 in the handle element 12.

A tongue 44 integral with the panel 40 is connected thereto along the bend line 45. The tongue 44 is on a plane at an acute angle to the plane of the panel 40, the bend line 45 defining the connection between the tongue and the panel. A substantially triangular aperture 46 is provided in the panel 40 having its base 47 extending substantially along the bend line 45. A portion of the material cut to form the aperture 46 may be bent rearwardly to form a reinforced flange 49 along the base 47 of the triangle.

The door is provided with a frame C extending to form a surface 50 in parallel spaced relation to the edge of the door. A stop or shoulder 51 usually forms a part of the frame C. This stop forms a shoulder against which the door may abut to limit its closing motion. The inclined groove 52 is cut in the stop 51, this groove being of proper length and depth to accommodate the handle element 12 in the closed position of the door illustrated in Figure 2. A headless screw or stud 53 is screwed into the frame C in position to extend through the elongated slot 13 and through the aperture 46 in closed position of the door.

In assembling the door the base plate 19 is first fitted into the notch in the edge of the door formed to accommodate the same. A base plate 20 is secured in place by the wood screw 31 or by any other suitable means. When secured in place the conical springs 33 are engaged between the latch plate and the door, the small diameter end of the springs being directed outwardly from the base plate.

The latch plate 39 is then placed in position by hooking the hook shaped flanges 34 and 35 through the opposed slots or notches 41 and 42. The panel 40 is positioned to overlie the springs 33.

The handle element 12 is then mounted in position. The hook shaped flanges 34 and 35 are extended through the notches 16 and 17 outwardly of the latch plate 39. An attaching screw 54 is then inserted through the aperture 18 in the handle element, through the aperture 43 in the latch plate 39, and through the aperture 55 in the base plate 19. The head of the screw 54 limits the outward swinging of the handle or limits the hinging movement of the handle in one direction. The springs 33 hold the latch plate and the handle element in this extreme position.

The stud 53 is then inserted in place in the frame and the latch is in readiness for operation. As the door B swings into closed position the outwardly projecting end of the stud 53 passes through the elongated slot 13 and strikes the tongue 44 of the latch plate 39. This action pivots the latch plate 39 about its hinged attachment to the hook shaped flanges 34 and 35 of the

base plate in a manner to compress the springs 33. The compression of the springs 33 continually increases until the head of the stud 53 drops into the aperture 46 of the latch plate. The springs 33 thereupon force the latch plate outwardly in such a way that the projecting end of the stud 53 is engaged in the aperture 46.

When it is desired to open the door the handle element 12 may be swung about its pivotal attachment with the hook shaped flanges 34 and 35 of the base plate either by pushing the handle end 10 toward the door or pulling the handle end 11 away from the door. This hinging movement of the handle element acts to swing the handle element toward the base plate 19, thus urging the latch plate 39 toward the base panel 20 and compressing the springs 33. The same pushing or pulling action used to pivot the latch also acts to swing the door away from its frame, thus disengaging the latch.

It will be noted that the handle element 12, the base plate 19, and the latch plate 39 may all be formed by a simple stamping operation. The conical springs 33 and the attaching screws as well as the locking stud 53 are readily available or can be easily manufactured at low cost. As a result the latch may be made at extremely low cost particularly in view of the fact that the latch does not have to be assembled before shipment.

In view of the extreme simplicity of the latch and in view of the fact that the latch must be disassembled before it may be attached to the door, it is most conveniently supplied in disassembled form with proper directions for installation.

No special tools are required for installation, it being only necessary to cut a notch in the door edge and frame and to secure the attaching screws in place.

It should be pointed out that while the handle element 12 may be assembled upon the projecting fingers 34 and 35 after the base plate 19 has been attached to the door edge, the handle must be applied while in an extreme pivotal position with the handle end 11 closely adjacent the surface of the door B. After the handle has been attached the limiting screw 54 is inserted in place, preventing the handle from pivoting into the extreme position mentioned. As a result the handle may not become accidentally disengaged and may only be removed after the limiting screw 54 has been removed. It should further be noted that the notches 16 and 17 in the handle and the notches 41 and 42 in the latch plate 39 form apertures through the handle and latch plate into which the projecting fingers on the base plate engage. It is convenient to form these apertures in the form of notches as illustrated, but obviously these apertures could be set in somewhat from the edge of the handle and latch plate if desired.

In accordance with the patent statutes, I have described the principles of construction and operation of my door latch, and while I have endeavored to set forth the best embodiment thereof, I desire to have it understood that obvious changes may be made within the scope of the following claims without departing from the spirit of my invention.

I claim:

1. A door handle comprising a U-shaped handle of sheet material, said handle having a pair of opposed notches therein on opposite sides thereof, a base plate designed for attachment to the door near an edge thereof, a pair of hook-

shaped fingers on said base plate engageable into said notches upon extreme pivotal movement of said handle, said fingers extending through said notches and overlying adjacent portions of said handle, means engaging said handle to normally limit the pivotal movement and to prevent said handle from being pivoted into said extreme pivotal position, and means resiliently urging said handle toward limited position.

2. A door latch comprising a substantially U-shaped handle designed to overlie the edge and adjacent side surfaces of a door, means engageable with said handle to pivotally connect said handle in door edge overlying position, a latch plate pivotally connected to said handle and underlying the same, said handle having a slot therein exposing a portion of said latch plate, said latch plate having an aperture therein in partial registry with said slot in said handle, said slot and aperture being designed to engage a keeper, and spring means interposed between said latch plate and the door.

3. A door latch comprising a substantially U-shaped handle designed to overlie the edge and adjacent side surfaces of a door, a base plate secured to the door, means pivotally connecting said base plate to the door, a latch plate pivotally connected relative to said handle and said base plate and underlying a portion of the handle, the handle having a slot therethrough exposing a portion of the latch plate, a shoulder in the latch plate between said handle and said base plate exposed through said slot, and spring means interposed between said latch plate and said base plate.

4. A door latch comprising a substantially U-shaped handle of strip material designed to overlie the edge and adjacent side surfaces of a door, said handle having spaced apertures therein, a base plate designed for attachment to the door, a pair of spaced projections on said base plate engageable into said apertures to pivotally attach said handle to said base plate, a latch plate between said base plate and said handle and pivotally mounted relative thereto, said handle having a slot therethrough exposing a portion of said latch plate, a shoulder in the exposed portion of said latch plate, spring means between said base plate and said latch plate, and means for limiting pivotal movement of said handle, said means holding said handle, said plate and latch plate assembled.

5. A door latch comprising a substantially U-shaped handle designed to overlie the edge of a door, a plate means designed for attachment to the door, a pair of spaced projecting fingers on said plate means, said handle having apertures therein for accommodating said projecting fingers to pivotally attach the handle to said plate means, a latch plate underlying a portion of said handle, said latch plate having spaced apertures therein through which said projecting fingers engage to pivotally attach the latch plate

relative to said handle and to said plate means, said handle, having a slot therein exposing a portion of said latch plate, and shoulder means in the portion of said latch plate exposed through said slot.

6. A door attachment including a base plate, means for securing said base plate to a door adjacent the edge thereof, a substantially U-shaped handle designed to overlie said base plate, said door edge, and the adjacent side surfaces of the door, a pair of projections on said plate, projecting outwardly from the door edge, portions of said handle which lie on a substantially common plane having a pair of spaced apertures therein for receiving said projections to pivotally connect said handle to the door.

7. A door latch designed for reception into a notch in an edge of a door, the latch including a base plate secured in said notch, a substantially U-shaped handle overlying said edge and said base plate, a pair of ears on said base plate and extending at substantially right angles thereto, said handle having a pair of apertures therein, said ears engaging into said apertures to hingedly connect said handle to said base plate, spring means urging said handle away from said base plate, means for limiting pivotal movement of said handle and latch means hingeable with the handle upon hinging movement thereof toward said base plate.

8. A door latch comprising a U-shaped handle designed to overlie the edge of a door, said handle having a substantially flat portion and a pair of spaced aperture means extending through said flat portion, said flat portion causing said spaced aperture means to lie on a substantially common plane, plate means on said door having projection means thereupon extending through said aperture means to hingedly connect the handle to the door, spring means urging said handle in one rotative direction, means for limiting the pivotal movement of said handle, and latch means pivotal with said handle upon pivotal movement thereof.
